UNITED STATES PATENT OFFICE.

GEORGE F. SIMONDS, OF FITCHBURG, MASSACHUSETTS, ASSIGNOR TO THE SIMONDS MANUFACTURING COMPANY, OF SAME PLACE.

IMPROVEMENT IN THE METHODS OF MAKING SERRATED SICKLE-SECTIONS.

Specification forming part of Letters Patent No. 90,593, dated May 25, 1869.

To all whom it may concern:

Be it known that I, G. F. SIMONDS, of Fitchburg, in the county of Worcester and State of Massachusetts, have invented an Improvement in the Manufacture of Serrated Sickle-Sections; and I do hereby declare that the following, taken in connection with the drawings which accompany and form part of this specification, is a description of my invention sufficient to enable those skilled in the art to practice it.

In serrating blanks for sickle-sections of harvesting-machines, the indentations or teeth are made upon, and so as to extend across, the beveled edge of the blank, so that as the cutting-edge is ground down in sharpening, the serrations of the cutting-edge are preserved.

As the indentations are first cut across the upper surface of the beveled edge of the blank, and not into the edge, like saw-teeth, the edge of the bevel has to be bent down, so that by facing off the edge to a plane of the under surface of the cutter the cutting-edge will be serrated.

The process heretofore practiced to obtain the serrated edge has been as follows: The bevel-edged blank is placed upon a suitable flat-surfaced bed, but with its beveled edge projecting over an incline upon the bed. By successive blows of a suitable cutter the upper surface of each beveled edge is now cut or toothed, each blow of the cutter not only making a groove or indentation in the surface of the blank, but also bending down the edge at the blow-given point to the surface of the incline over which the edge projects. When this cutting has been accomplished the under surface of the edge of the blank will be below the plane of the under surface of the blank. Such bent-down edge is then ground off to the plane of the under surface of the plate, the edge being thereby formed into a serrated cutting-edge.

Sickle-sections made by this process are imperfect, in that as the cutting-edge of the cutter has to be parallel to the surface of the incline down to which the edge is to be bent, the part of the beveled edge back of the bend so formed is not cut to the same depth as the part of the edge bent down, in consequence of which the serrations of the cutting-edge di-

minish in depth as the edge of the section is ground back in sharpening; and, also, in that as the bending action of the cutter does not extend to the point of the section, the edge of the section adjacent to such point protrudes beyond the points of the cutting-teeth, (when the edge has been ground off,) thereby impairing the cutting action of the section.

To obviate these objections I support the beveled edge upon a flat bed under the action of the cutter, the cutting-edge of the cutter being parallel to the surface of the beveled edge of the blank, thus causing the grooves to be cut to a uniform depth throughout each; and having thus effected the cutting, I remove the blank from the flat bed, and bend down the whole edge of the bevel at once, (by any suitable mechanism,) after which the bent edge is ground off to a plane with the bottom surface of the plate, thus making the serrated cutting-edge. It is in this process for producing the serrated edge that my improvement consists—that is to say, a process consisting in first cutting the grooves across the beveled surfaces of the section, next bending down at one operation the edge of the bevel, and, lastly, grinding off the edge thus bent down to a plane with the under surface of the blank plate.

The drawings represent a sickle-section made in accordance with my process, and also a section made by the old process, above described.

A shows a top view of one of my sections finished. B is a section, showing the edge after being bent and before being ground off. C is a similar section, showing the finished edge. D is a top view of the finished section made by the old process described. E shows the edge of such section before it is ground off.

In my process, the blank being supported at its beveled edge upon a flat bed, each groove is cut to a uniform depth throughout, as seen at A, and at B and C, and the entire length of edge on either side of the point of the section being then bent down, as seen at B, and the bent edge being then ground down to the plane of the under surface of the plate, the cutting-edge will be left as seen at A and C, or so that, as the plate is reduced in thickness in resharpening, the serrations or teeth of the cutting-edge are kept of the same size, whereas,

if the edge of the blank be bent down by the blow of the cutter, each groove decreases in depth back from the cutting-edge, as seen at D and E, and the blade, near the point, projects out beyond the line of the point of the cutting-teeth, as seen at D.

I claim—

1. The improved process of serrating sickle-sections, by first cutting the grooves on the beveled surface upon a flat bed, next bending

down the whole edge of the bevel, and, finally, grinding off the edge, substantially as described.

2. Sickle-sections made by the improved process described.

GEO. F. SIMONDS.
